UNITED STATES PATENT OFFICE.

ADOLPH H. SMITH AND GEORGE W. NIBBE, OF CHICAGO, ILLINOIS.

ANTICREEPING DEVICE FOR RAILS.

1,168,525.

Specification of Letters Patent. Patented Aug. 25, 1914.

Application filed December 23, 1913. Serial No. 808,036.

To all whom it may concern:

Be it known that we, ADOLPH H. SMITH and GEORGE W. NIBBE, citizens of the United States, residing at Chicago, in the county 5 of Cook and State of Illinois, have invented certain new and useful Improvements in Anticreeping Devices for Rails, of which the following is a specification.

Our invention relates in general to rail-way track fastening devices, and more particularly to rail anti-creepers.

It is well-known that the passage of trains over railway tracks tends to shift the tracks longitudinally in the direction of the movement of the trains. When the trains run in opposite directions on the same tracks the tendency of the tracks to creep in one direction is compensated by their tendency to creep in the opposite direction, but when the 20 trains run only in one direction, as is the case with double track roads, the creeping or shifting of the rails is so considerable as to be dangerous unless prevented.

The primary object of our invention is to 25 provide improved anchoring devices for railroad rails to prevent longitudinal creeping or shifting thereof, which will securely retain the rails against longitudinal movement relatively to the ties, and will be automatically actuated by any tendency of the rails 30 to creep to grip the rails more securely and effect a more rigid resistance to the creeping tendency.

A still further object of our invention is 35 to provide an improved anti-creep for railroad rails which will be simple in construction, convenient in application, efficient in operation, and durable in use.

Our invention will be more fully disclosed 40 hereinafter with reference to the accompanying drawings, in which the same is illustrated in several convenient and practical forms, and in which—

Figure 1 is a sectional view on line 1, 1, 45 Fig. 4; Fig. 2 a perspective view of one of the clamping members; Fig. 3 a perspective view of the other clamping member; Fig. 4 a plan view; Fig. 5 a perspective view of the wedge which engages the clamping members; Figs. 6 and 7 views similar to Figs. 1 and 4 illustrating a modified form of our invention; Fig. 8 a perspective view of one of the clamping members of the form of our invention shown in Figs. 6 and 7; Figs. 9 50 and 10 views similar to Figs. 1 and 4 illustrating still another form of our invention;

tion; Fig. 11 a perspective view of one of the clamping members of the form of our invention shown in Figs. 9 and 10; Fig. 12 a perspective view of the other of the said 60 clamping members; and Fig. 13 a detail sectional view on line 13, 13, Fig. 12.

Similar reference characters are used to designate similar parts in the several figures of the drawings.

Referring more particularly to Figs. 1 to 5, inclusive, reference letter A indicates a railroad rail, the base *a* of which is supported upon a tie B. C and D designate interlocking clamping members which are adapted to be secured to the base of the rail adjacent the tie B and through the medium of the wedge G to prevent movement of the rail toward the tie. The clamping members C and D are provided with upwardly and inwardly extending flanges *c* and *d*, respectively, which are adapted to engage the opposite sides of the base *a* of the rail. The portions of the clamping members which extend beneath the base of 30 the rail are oppositely cut away, as shown at *e* and *f*, respectively, so that the two clamps transversely align. The clamping members are provided with downwardly and inwardly inclined flanges E and F, respectively, co-extensive in length with the width of the portions of the clamping members which underlie the rail base. The flanges E and F, therefore, project across the cut away portions *e* and *f*, respectively, of the 35 clamping members. G designates a wedge having a head *g* adapted to bear against the vertical surface of the tie B beneath the rail base. The flanges E and F are tapered to correspond with the taper of the wedge 40 G so that the wedge will uniformly engage the said flanges throughout their length and thereby when moved relatively to such flanges exert a uniform pull upon the 45 clamping members toward the rail base.

Our improved anti-creep may be conveniently applied by first engaging the clamping members C and D with the opposite edges of the base of the rail at a distance farther away from the tie B than the 50 length of the wedge G. The wedge G is then inserted between the overlapped flanges E and F, and the clamping members, together with the wedge, moved toward the tie until the head *g* of the wedge rests 55 against the tie. The clamping members are then forced toward the tie, and consequently

moved relatively to the wedge, as far as possible, so as to be securely clamped to the rail base. Any tendency of the engaged portion of the rail to creep toward the tie will 5 cause the wedge G to more forcibly engage the flanges E and F and thereby effect a tighter biting of the flanges c and d of the clamping members against the rail base.

In Figs. 6, 7 and 8 we have shown a 10 slightly modified form of our invention in which the flanges c' and d' of the clamping members C' and D' are not located in transverse alinement, but are staggered, as clearly shown in Fig. 7. In this form of our invention the clamping members are provided with downwardly extending curved flanges E' and F', which are tapered longitudinally to conform to the taper of the wedge G'. The flange E' extends beyond the adjacent 15 portion of the member C' so as to underlie the portion of the clamp D' which lies beneath the rail base. In a similar manner the flange F' extends beyond the portion of the clamping member C', which underlies 20 the rail base so as to extend across the under surface of the portion of the clamping member D' which underlies the rail base. The form of our invention shown in Figs. 6, 7 and 8 is applied to the rail in the manner 25 above described in connection with Figs. 1 to 5, inclusive, and operates substantially the same, except that the movement of the wedge relatively with respect to the engaged tapered flanges E' and F' draws the flanges 30 c' and d' of the clamping members into gripping relation with portions of the rail base which do not transversely aline. In this form of our invention, as in the form 35 illustrated in Figs. 1 to 5, inclusive, the two clamping members interlock beneath the rail base in that each is provided with a flange extending beneath the base portion of the other, thereby affording an extended engagement with the wedge.

In Figs. 9 to 13, inclusive, we have illustrated another specific embodiment of our invention in which the wedge is formed integrally with one of the clamping members. In said figures, reference character C² designates one of the clamping members which is provided with an upwardly and inwardly projecting flange c² to engage the rail base, and is also provided with the downwardly extending curved and tapered flange E² projecting across the cut away portion c². The coöperating clamping member D² is also provided with an upwardly and inwardly extending flange d² to engage the opposite edge of the rail base. Formed integrally with the 50 portion of the clamping member D², which is adapted to underlie the rail base, is a wedge G² provided with a head g². This clamping member is cut away, as shown at F², to receive the portion of the coöperating clamping member to which the flange E²

thereof is connected. In this form of our invention the clamping member D² is engaged with the rail base adjacent the tie B and with the head g² of the wedge abutting against the adjacent vertical surface of the tie. The coöperating clamping member C² is then engaged with the opposite side of the rail base at a distance sufficiently far from the tie for the flange E² to engage with the wedge G². The member C² is then 75 moved toward the tie so as to interlock with the coöperating clamping member D². The two clamping members are forced toward the tie as tightly as possible so as to produce a tight gripping action between the clamping members and the rail base, owing to the relative movement of the wedge and the flange E². Any tendency of the portion of the rail base which is engaged by the clamping members to move toward the tie tends 80 to move the member D² relatively to the member C² owing to the bearing of the head g² of the wedge against the tie.

From the foregoing description it will be observed that we have invented an improved 90 anchoring device for preventing the creeping or shifting of rails relatively to the adjacent ties, which comprises transversely overlapping and longitudinally interlocked clamping members having extended longitudinal engagement with an interposed 95 wedge so that the two members will be uniformly and tightly drawn into gripping relation with the rail base through the medium of the wedge interposed between the clamp- 100 ing members and the adjacent tie.

We claim:

1. The combination with a railroad rail and supporting tie therefor, of a pair of clamping members engaging the opposite 105 sides of the rail base and having transversely overlapping portions below the rail base, one of said members having on the end of its transversely overlapping portion a depending flange longitudinally overlapping the 110 adjacent portion of the other member, and means bearing against the tie and engaging said depending flange to draw said members into tightly gripping contact with the rail base.

2. The combination with a railroad rail and supporting tie therefor, of a pair of clamping members engaging the opposite 115 sides of the rail base and having longitudinally and transversely overlapping portions below the rail base, and means bearing against the tie and extending between said overlapped portions to draw said members into tightly gripping contact with the rail base.

3. The combination with a railroad rail and supporting tie therefor, of a pair of clamping members engaging the opposite sides of the rail base comprising transversely overlapping portions beneath the rail base,

115

120

125

130

and also comprising depending longitudinally overlapping projections on the ends of said transversely overlapped portions, and means bearing against the tie and extending 5 between said depending projections for drawing said members into tightly gripping contact with the rail.

4. The combination with a railroad rail and supporting tie therefor, of a pair of 10 clamping members engaging the opposite sides of the rail comprising transversely overlapping portions extending beneath the rail base, each of said transversely overlapping portions being cut away to receive the 15 other portion, the ends of said overlapping portions having depending flanges thereon, and means bearing against the tie and interposed between said flanges to draw said members into tightly gripping contact with 20 the rail.

5. The combination with a railroad rail and supporting tie therefor, of a pair of clamping members engaging the opposite sides of the rail comprising transversely 25 overlapping portions extending beneath the

rail base, each of said transversely overlapping portions being cut away to receive the other portion, the ends of said overlapping portions having depending flanges diverging toward the tie, and a 30 wedge bearing against the tie and extending between said flanges to draw said members into tightly gripping contact with the rail.

6. In a device for preventing the creeping 35 of railroad rails, a clamping member comprising a flange to engage the rail base, a portion to extend beneath the rail base, and a depending flange at the edge of said portion, said portion being cut away to receive a similar portion of a coöperating clamping 40 member and to permit said depending flange to longitudinally overlap such coöperating member.

In testimony whereof, we have subscribed our names.

ADOLPH H. SMITH.
GEORGE W. NIBBE.
